(57) CLAIM

The ornamental design for a cosmetic container, as shown and described.

DESCRIPTION

FIG. 1 is a front, top, and left side perspective view of a cosmetic container showing my new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is a rear, bottom, and right side perspective view thereof; and,

FIG. 9 is an enlarged view of portion 9 shown in FIG. 1.

The logo “XUKONI” & “±” shown on top end in FIGS. 1 and 6 is a trademark and the name of the owner of the trademark is “Ju Yeon PAE”.

The dot-dash broken lines encircling portions of the claimed design that are illustrated in enlargement form no part of the claimed design.
